ROTARY BROOM SWEEPER
John W. Jones, % Jones Bros. Dirt Contractors,
P.O. Box 3983, Odessa, Tex.
Filed Dec. 26, 1962, Ser. No. 246,901
5 Claims. (Cl. 15—82)

This invention relates to brooms and more particularly to a powered rotary broom for street sweeping and related uses.

The sweeper is mounted on a standard farm tractor which has a hydraulic lift mechanism. These lift mechanisms are called "three point hitches" or "A frames." The entire sweeper may be raised or lowered at will of the operator. In addition to this, the broom is mounted to be locked in one of a plurality of pivoted positions about a vertical axis so that the sweepings may be thrown to the right or left or straight ahead. This vertical axis pivot introduces the problem of transmitting power from the tractor to the broom. I have solved this by mounting a right angle gear box powered from the tractor on that portion of the sweeper which is attached to the tractor without rotation. From this point a U joint is located directly below the pivot so that the sweeper may pivot from right or left and the U joint accommodates this movement.

An object of this invention is to provide an improved powered rotary broom sweeper.

Another object of this invention is to provide such a sweeper which is mounted on a standard vehicle so that it may be raised to a transport position or lowered into operating position simply and easily.

A further object is to provide a sweeper which is spring supported as to the contact with the surface being swept, for better sweeping and to prevent damage to the broom.

A further object is to provide such a sweeper which is mounted for selected rotation about a vertical axis.

Still further objects are to achieve the above with a device that is sturdy, compact, durable, simple, versatile, and reliable, yet inexpensive and easy to manufacture and operate.

The specific nature of the invention as well as other objects, uses, and advantages thereof will clearly appear from the following description and from the accompanying drawing, the different views of which are not necessarily to the same scale, in which:

FIG. 1 is an elevational view of a sweeper according to my invention attached to the towing vehicle shown in phantom.

FIG. 2 is a plan view of the sweeper according to my invention attached to a towing vehicle shown in phantom, with the broom cover removed for clarity.

FIG. 3 is a perspective view of the sweeper with some parts broken away and the broom cover removed for clarity.

FIG. 4 is a partial sectional view of the spindle taken on line 4—4 of FIG. 2.

FIG. 5 is a partial plan view showing the spindle illustrating the adjustment about the vertical axis.

As may be seen in the accompanying drawings, broom 10 is a cylindrical broom which is mounted on shaft 12. Inasmuch as these brooms are standard items in commerce which are available on the market for this purpose they will not be further discussed here. The shaft 12 is journalled in bearings 14 which are mounted on frame or yoke 16, which in plan forms a rectangle. The bearings 14 are mounted on the short sides 18 of this rectangular frame. Generally, the frame 16 lies in a horizontal plane and the broom shaft 12 is horizontal and level with the surface to be swept.

Adjusting wheels 20 are mounted at the rear corners

2

of the frame 16. These wheels 20 are mounted for rotation about a vertical axis as well as a horizontal axis so that in fact they are castors. Preferably they have pneumatic tires. Threaded shaft 22 rises from above castors

5 20 and extends through a hole within the frame 16. Spring 24 surrounds the threaded shaft 22 and extends between the frame 16 and the top of the castors 20. The downward movement of the castors 20 is limited by a pair of lock nuts 26 which are attached to the threaded shaft 10 22 above the frame 16. By this arrangement the height of the rear of the sweeper may be adjusted. I.e. the castors 20 contact the ground and the springs 24 push the frame 16 upward. The height the frame 16 will rise upward is governed by setting of the lock nuts 26.

15 Standard agricultural vehicle 28 in the form of a tractor is used to carry the sweeper. These tractors as standard and conventional equipment include a pair of lifter arms 30 which are pivoted at 31 at their forward end to the tractor 28 with the back of the arms extending rearward.

20 The arms 30 may be rotated about the point 31 by lifter links 32 which extend from the arms 29 to a hydraulic power lift system. The connection to the sweeper includes a pair of spindle brackets 34 which extend forward from the sweeper. Coupling rod 36 is the third element of the "three point hitch." It extends from a

25 point on the tractor 28 to the sweeper. The coupling rod 36 is adjustable as to length by a turn-buckle or other means known to the art. As indicated before, the "three point hitches" or "A frames" are well known in the agricultural art and therefore not further described here.

Vertical spindle 38 is attached to the forward long side 30 of the rectangular frame 16. Sleeve 42 is mounted below frame 16 for rotation about the spindle 38 by suitable bearings. The brackets 34 are welded to the

35 sleeve 42. Second sleeve 44 is journalled to the spindle 38 and one end of the coupling rod 36 is attached to this sleeve. As the spindle 38 is attached to the frame 16 and as the sleeves 42 and 44 are attached to the tractor, by this means the sweeper with its frame 16 is mounted for rotation about a vertical axis (spindle 38) relative to the tractor. The brackets 34 and rod 36 provide means for raising and lowering the frame 16 and therefore the sweeper as a whole.

40 The height of the broom 10 or the pressure with which it rides against the ground, may be adjusted by different means. First it will be assumed that when the lift arms 30 are in the lower position that they are pivoted freely so that they can go lower than in the position they are set.

Otherwise, of course, it will be understood that the position of the broom could be adjusted by the hydraulic lifter by adjusting the lifter arms 30. However assuming they are free to rotate in the lower position; the position of the broom 10 may be controlled by two ways. One way is by adjusting the length of the coupling rod 36.

45 If the coupling rod 36 is shortened the frame 16 will angle forward. Inasmuch as the broom 10 is located forward of the castors 20 the broom 10 will press with more force against the surface. On the other hand if the coupling rod 36 is lengthened the frame 16 will be tilted back and the broom 10 will be lifted from the surface. In addition to this adjustment the castors 20 may be raised or lowered by the position of the lock nuts 26 on the threaded shaft 22.

50 Power is supplied by the towing vehicle, tractor 28, from the power take-off. Power drive shaft 46 is attached to the tractor in a conventional manner and extends behind it to gear box 48 which is mounted upon sleeve 42. The drive shaft 46 is provided with U joints and a spline expansion joint as is customary in the art. Therefore power is supplied to the gear box 48 regardless of the position or angular disposition of the gear box 48. Since

the gear box 48 is located on the sleeve 42, the angular disposition will not be changed radically. Broom drive shaft 50 is journaled in bearing 52 which is attached to the frame 16 at the out-board end of the shaft 50. The other end of shaft 50 is connected by U joint 54 to the gear box 48. The U joint 54 is located directly below spindle 38. Therefore it is possible for the frame 16 to be rotated to different positions and power still supplied to the drive shaft 50. I.e. any angular change will be accommodated by the U joint 54. The broom 10 is driven by chain 56 which interconnects sprocket 58 mounted on the shaft 50 and sprocket 60 mounted upon broom shaft 12.

Broom guard 62 prevents the sweepings of the broom 10 from being thrown on the operator.

The spindle 38 extends through circular plate 64 welded on top of side 40 of frame 16, and through circular plate 66 welded to the bottom of second sleeve 44. The plates 64 and 66 have a plurality of holes 68 therethrough so that the sweeper may be maintained in a plurality of positions by pin 70. FIG. 2 illustrates some of the positions by dashed lines.

Therefore it may be seen that I have provided a simple yet effective sweeper mechanism to fulfill the objects set forth above.

It will be apparent that the embodiment shown is only exemplary and that various modifications can be made in construction, materials, and arrangement within the scope of the invention as defined in the appended claims.

I claim as my invention:

1. A sweeper comprising:
  - (a) a horizontal frame,
  - (b) a cylindrical broom journaled to said frame for rotation about a horizontal axis,
  - (c) two wheels attached to the rear of the frame,
  - (d) a vertical spindle attached to the front of the frame,
  - (e) a bracket journaled for rotation on said spindle,
  - (e') a coupling rod journaled for rotation on said spindle and connected to a towing vehicle,
  - (f) means interconnecting said bracket and the towing vehicle for raising the bracket and thus the frame from a means on the towing vehicle,
  - (g) a gear box attached to the bracket,

(h) means for driving said gear box from the towing vehicle,

(i) a shaft journalled to the frame for rotation,

(j) means for rotating the broom responsive to rotation of the shaft,

(k) said gear box having a driving connection to said shaft, and

(l) said driving connection from the gear box to the shaft including a U joint which is aligned with the axis of said spindle.

2. The invention as defined in claim 1 wherein said means interconnecting said bracket and the towing vehicle permits tilting the frame forward or back by said coupling rod so that the broom is closer or further from the ground relative to the wheels.

3. The invention as defined in claim 1 wherein the wheels are adjustable as to height, thereby adjusting the height of the broom.

4. The invention as defined in claim 2 wherein:

(m) a sleeve is utilized in journalling said coupling rod for rotation on said spindle, and

(n) said coupling rod is adjustable as to length whereby the tilt of the frame is adjusted.

5. The invention as defined in claim 4 with the addition of:

(o) a circular plate attached to the sleeve,

(p) a circular plate attached to the frame,

(q) each plate having a plurality of holes therethrough,

(r) said spindle extending through both plates, and

(s) a pin through one of the holes in each plate for maintaining the frame in adjusted angular position.
